UNITED STATES PATENT OFFICE.

EDWIN N. LIGHTFOOT, OF MILWAUKEE, WISCONSIN, ASSIGNOR TO THE CUTLER-HAMMER MFG. CO., OF MILWAUKEE, WISCONSIN, A CORPORATION OF WISCONSIN.

METHOD OF MAKING ELECTRIC HEATERS.

Application filed February 5, 1921, Serial No. 442,882. Renewed February 2, 1927.

This invention relates to the method of making electric heaters and machine therefor.

More particularly the invention relates to 5 the method of and means for insulating the resistor of an electric heater from the enclosing jacket thereof.

One of the objects of the invention is to 10 provide an improved method of insulating the resistor of an electric heater.

Another object is to provide an improved 15 method of insulating the resistor of an electric heater from the enclosing jacket thereof with insulation in one form and subsequently changing the physical characteristics of the insulation.

Other objects and advantages will hereinafter appear.

The views of the drawings are:

20 Fig. 1 is a side elevation of a filling machine;

Fig. 2 is an enlarged vertical section through the filling head shown in Fig. 1;

25 Fig. 3 is an enlarged horizontal section on line 3—3 of Fig. 1;

Fig. 4 is a transverse section on line 4—4 of Fig. 3; and

Fig. 5 is a top plan of the filling machine.

The method in general consists of introducing between the resistor and the tubular jacket of an electric heater insulation in one form, such as a plastic mass and thereafter changing the form into a hard

30 compact mass by drying the insulation and thereafter compressing and compacting the insulation in the jacket and around and about the resistor.

35 The material used for the plastic may be any suitable electrical insulating material, such as magnesium oxide, preferably in powdered form mixed with sufficient kaolin, china clay, ball clay or any such material as will when mixed with a liquid such as water give a plastic mass that will flow

40 under pressure.

45 The machine, by means of which a tubular jacket of an electric heater may be filled with insulation, may consist of a filling

head 1, to which a tubular jacket may be attached for filling, and a container 2 for 50 the insulating material, connected to the filling head by means of a tube 3.

The filling head 1 may be provided with a central chamber 4 to which one end of a tubular jacket 5 may be connected by means 55 of a joint or bushing 6 and pliable packing material 7, for example felt. The packing 7 when compressed, by screwing the bushing 6 into the filling head, grips the jacket 5 thereby holding it firmly in position and also forms a tight joint between the jacket and filling head to prevent egress of insulation when the jacket is being filled.

The container 2 comprises a cylinder or barrel 8 with an internally travelling head 65 or disc 9 provided with a threaded aperture into which a threaded rod 10 may be screwed to move the head from one end of the barrel to the other. The threaded rod 10 may be rotated by a handle 11 or other 70 suitable means.

The barrel 8 may be provided with an internal slot 12 to prevent rotation of the disc 9.

Before the heater jacket 5 is attached to 75 the filling head, a plug terminal 13 with a resistor 14 connected thereto and extending upwardly within the jacket is inserted in the lower end of the heater jacket. The free end of the resistor is preferably connected to some means such as a drum fastened to a ratchet 15 for the purpose of holding the resistor taut.

For the purpose of centering the resistor within the tubular jacket and to insure 85 against imperfect filling of the jacket, a filling tube 16 surrounding the resistor is inserted through the filling head 1 and extended to the bottom portion of the heater jacket.

A joint or bushing 17 surrounding the filling tube 16 is screwed into the filler head to prevent egress of the insulating material.

After the tubular jacket has been 95 attached to the filling head, the filling tube

inserted therein and the container filled with plastic insulating material, the handle 11 may be turned to force the insulation out of the container through the tube 3 into the chamber 4 down into the heater jacket between the walls thereof and the filling tube to the bottom of the heater jacket.

When the plastic insulation reaches the bottom of the jacket 5 it then flows up through the filling tube surrounding the resistor. The filling tube may be withdrawn gradually as the plastic flows up around the resistor. Consequently when the operation is completed and the filling tube entirely withdrawn the heater jacket is completely filled and the resistor completely surrounded by and embedded in the plastic.

The filling tube 16 may be provided with a set of radially extending lugs or fingers 18 to keep the tube centered with respect to the heater jacket.

After the heater jacket is completely filled in the manner described a plug terminal is inserted in and securely fastened to the other end of the jacket.

The plastic insulation may then be dried into a hard compact mass by passing current through the resistor.

After the insulation has been thoroughly dried the heater jacket may be contracted crosswise by swaging or other suitable means to thereby break up the insulation into fine particles or powder, and compress and compact the powdered insulation around and about the resistor.

The heater jacket may contracted by a swaging machine such as disclosed in Patent 1,359,400, dated November 16, 1920.

While but one embodiment has been shown and described, various other embodiments and adaptations may be made of the invention contained herein.

The invention claimed is:

1. The method of insulating the resistor of an electric heater from the enclosing jacket thereof, which comprises surrounding the resistor with insulation in one form and subsequently changing the physical characteristics thereof.

2. The method of insulating the resistor of an electric heater from the enclosing jacket thereof, which comprises surrounding the resistor with insulation in one form and subsequently altering the physical characteristics thereof and compressing and compacting the same in the jacket and around and about the resistor.

3. The method of insulating the resistor of an electric heater from the enclosing jacket thereof which comprises surrounding the resistor with insulation in plastic form and subsequently altering the physical characteristics thereof.

4. The method of insulating the resistor

of an electric heater from the enclosing jacket thereof which comprises surrounding the resistor with insulation in plastic form and subsequently drying the insulation.

5. The method of insulating the resistor of an electric heater from the enclosing jacket thereof which comprises surrounding the resistor with insulation in plastic form and subsequently reducing the insulation to a hard compact mass.

6. The method of insulating the resistor of an electric heater from the enclosing jacket thereof which comprises surrounding the resistor with insulation in plastic form and subsequently drying the insulation and reducing it to powder formation.

7. The method of insulating the resistor of an electric heater from the enclosing jacket thereof which comprises surrounding the resistor with insulation in plastic form and subsequently drying the insulation and compressing and compacting the same in the jacket and around and about the resistor.

8. The method of insulating the resistor of an electric heater from the enclosing casing thereof which comprises centering the resistor within the heater casing and surrounding the resistor with insulation in one form and subsequently changing the physical characteristics thereof.

9. The method of insulating the resistor of an electric heater from the enclosing casing thereof which comprises centering the resistor within the heater casing, surrounding the resistor with insulation in one form and subsequently altering the physical characteristics thereof and compressing and compacting the same in the jacket and around the resistor.

10. The method of insulating the resistor of an electric heater from the enclosing jacket thereof, which comprises positioning the resistor within the jacket, introducing into the jacket an emulsion of the insulation and a liquid, and then subjecting the insulation to treatment to remove the liquid therefrom and to bring the particles of insulation into intimate contact to minimize the voids between the particles.

11. The method of insulating the helical resistor of an electric heater from the enclosing jacket thereof, which comprises positioning the resistor within the jacket, introducing the insulation into said jacket with a liquid medium, and then subjecting the insulation to treatment to remove the liquid therefrom and compact the mass thereof.

12. The method of insulating the resistor of an electric heater from the enclosing casing thereof, which comprises filling said casing with insulation in plastic form to embed said resistor, positively centering said resistor, during the filling operation, heating said insulation to form a hard compact mass, and

then disintegrating said mass while maintaining said resistor centered with respect to the casing.

13. The method of insulating the helical resistor of an electric heater from the enclosing casing thereof, which comprises surrounding the resistor with insulation in plastic form and subsequently altering the

physical characteristics thereof by the application of heat, and compressing and compacting the same in the casing and around and about the resistor. ¹⁰

In witness whereof, I have hereunto subscribed my name.

EDWIN N. LIGHTFOOT.
